216,886

CASING FOR A VEHICLE AIR CONDITIONER

Charles F. Myers, P.O. Box 886,
Denison, Tex. 75020

Filed Nov. 26, 1968, Ser. No. 14,670

Term of patent 14 years

Int. Cl. D23—04
U.S. Cl. D23—142

FIG. 3

FIG. 2

FIG. 1

FIG. 4

FIG. 5

FIG. 6

FIG. 7

FIG. 8

FIGURE 1 is an isometric view of a casing for a vehicle air conditioner showing my new design;

FIGURE 2 is a front elevation;

FIGURE 3 is a top plan view;

FIGURE 4 is a bottom view;

FIGURE 5 is a rear elevation;

FIGURE 6 is an end elevational view of one end;

FIGURE 7 is an end elevational view of the opposite end thereof; and,

FIGURE 8 is a sectional view taken on line 8-8 of FIGURE 4.

I claim:

The ornamental design for a casing for a vehicle air conditioner, substantially as shown and described.
